CLAIM

The ornamental design for beverageware, as shown and described.

DESCRIPTION

FIG. 1 is a perspective view of a first embodiment of a beverageware showing my new design;

FIG. 2 is a left side view thereof;

FIG. 3 is a right side view thereof;

FIG. 4 is a front view thereof;

FIG. 5 is a rear view thereof;

FIG. 6 is a top view thereof;

FIG. 7 is a bottom view thereof;

FIG. 8 is a perspective view of a second embodiment of a beverageware;

FIG. 9 is a left side view thereof;

FIG. 10 is a right side view thereof;

FIG. 11 is a front view thereof;

FIG. 12 is a rear view thereof;

FIG. 13 is a top view thereof;

FIG. 14 is a bottom view thereof; and,

FIG. 15 is a left side view of a third embodiment of a beverageware with upper and lower bands having contrasting appearances, the perspective, right side, front, rear, top and bottom views correspond to FIGS. 8-14, except for the upper and lower bands of the third embodiment have contrasting appearances.

The broken lines in the drawing depict portions of the beverageware that form no part of the claimed design. The dash-dot lines in the drawing depict bounds of the claimed design that form no part of the claimed design. The difference in cross-hatching patterns on the upper and lower bands of FIG. 15 is used to indicate a contrast in appearance.
